COMBINED FACE PLATE AND LOCKED COVER FOR ELECTRICAL DEVICES

Jack H. Gaines, Seal Beach, Calif., assignor, by mesne assignments to Sierra Electric Inc., Gardena, Calif., a corporation of Wisconsin

Filed Sept. 5, 1967, Ser. No. 8,496

Term of patent 14 years

(Cl. D26—13)

FIG. 1.

FIG. 3.

FIG. 4.

FIG. 2.

FIG. 1 is a view showing in perspective my new design for a combined face plate and locked cover for electrical devices;

FIG. 2 is a front elevation of FIG. 1;

FIG. 3 is a plan view of FIG. 2; and

FIG. 4 is a left side elevation of FIG. 2.

The broken lines are for illustrative purposes only.

I claim:

The ornamental design for a combined face plate and locked cover for electrical devices, substantially as shown and described.
